(57) **CLAIM**

The ornamental design for an electric bean grinder, as shown and described.

DESCRIPTION

FIG. 1 is a first perspective view of an electric bean grinder showing the new design.

FIG. 2 is a magnified perspective view of section 2 in FIG. 1 of the electric bean grinder.

FIG. 3 is a second perspective view of the electric bean grinder of FIG. 1.

FIG. 4 is a third perspective view of the electric bean grinder of FIG. 1 with the lid open.

FIG. 5 is a fourth perspective view of the electric bean grinder of FIG. 1 in a disassembled state.

FIG. 6 is a front view of the electric bean grinder of FIG. 1.

FIG. 7 is a rear view of the electric bean grinder of FIG. 1.

FIG. 8 is a side view of the electric bean grinder of FIG. 1.

FIG. 9 is an opposite side view of the electric bean grinder of FIG. 1.

FIG. 10 is a top view of the electric bean grinder of FIG. 1; and, FIG. 11 is a bottom view of the electric bean grinder of FIG. 1. The dot-dash broken lines depict the boundary of the enlarged views and form no part of the claimed design. The evenly spaced broken lines showing portions of the electric bean grinder form no part of the claimed design.
